Primary Examiner—M. N. Pandozzi(74) *Attorney, Agent, or Firm*—Wallenstein & Wagner, Ltd.(57) **CLAIM**

What is claimed is the ornamental design for a covered casserole, as shown and described.

DESCRIPTION

FIG. 1 is a perspective view of a covered casserole showing our new design;

FIG. 2 is a top view of the covered casserole shown in FIG. 1;

FIG. 3 is a front view of the covered casserole shown in FIG. 1, the rear view being identical thereto;

FIG. 4 is a side elevation view of the covered casserole shown in FIG. 1, the opposed side elevation view being identical thereto;

FIG. 5 is a bottom view of the covered casserole shown in FIG. 1; and,

FIG. 6 is a perspective view of a covered casserole showing a second embodiment of our new design.

Features shown in broken lines form no part of the claimed design.

The broken lines in the drawings are for illustrative purposes only and form no part of the claimed design.
